UNITED STATES PATENT OFFICE.

CLAUDE COLLER, OF NEW YORK, N. Y., ASSIGNOR TO ALBERT BEHREND
AND JOSEPH ROTHSCHILD, OF NEW YORK, N. Y., A FIRM.

DESIGN FOR AN INFLATABLE TOY.

No. 38,185.

Specification for Design.

Patented Aug. 21, 1906.

Application filed June 25, 1906. Serial No. 323,393. Term of patent 3½ years.

To all whom it may concern:

Be it known that I, CLAUDE COLLER, a citizen of the United States, residing in the city of New York, borough of Brooklyn, county of Kings, and State of New York, have invented a new, original, and ornamental Design for an Inflatable Toy, of which the following is a specification.

My new design is illustrated in the accompanying drawing, forming part hereof, where-

in the figure is a perspective view of an inflatable toy embodying my design.

I claim—

The ornamental design for an inflatable toy, as shown.

CLAUDE COLLER.
